[57] CLAIM

The ornamental design for an engaging strip for attachment of documents, as shown.

DESCRIPTION

FIG. 1 is a top perspective view of an engaging strip for attachment of documents showing my new design;

FIG. 2 is a side elevational view thereof, the undisclosed side being a mirror image; and

FIG. 3 is a top plan view thereof, the undisclosed bottom being smooth and plain.

The broken lines shown in FIG. 1 are for illustrative purposes only and form no part of the claimed design.

FIG. 1

FIG. 3

UNITED STATES PATENT AND TRADEMARK OFFICE
CERTIFICATE OF CORRECTION

PATENT NO. : Des. 319,260
DATED : August 20, 1991
INVENTOR(S) : DUBAJ

It is certified that error appears in the above-identified patent and that said Letters Patent is hereby corrected as shown below:

On the cover page, item [76], "11" should read
--1--.

Signed and Sealed this
Fourth Day of May, 1993

Attest:

MICHAEL K. KIRK

Attesting Officer

Acting Commissioner of Patents and Trademarks
